[57] **CLAIM**

The ornamental design for proximity-sensor mount for a fluid pressure cylinder, as shown and described.

DESCRIPTION

FIG. 1 is a front elevational view of proximity-sensor mount for a fluid pressure cylinder embodying my new design; FIG. 2 is a rear elevational view thereof;

FIG. 3 is a top plan view thereof;

FIG. 4 is a bottom plan view thereof;

FIG. 5 is a left side view thereof;

FIG. 6 is a cross-sectional view thereof taken along line 6—6 in FIG. 1; and,

FIG. 7 is a reduced scale environmental perspective view thereof.

The proximity sensor, which is insertable into the proximity sensor mount, and the fluid pressure cylinder shown in FIG. 7 are shown for illustrative purposes only and form no part of the claim design.
